UNITED STATES PATENT OFFICE.

EDWARD DEAN MAHAN AND JAMES IRA MAHAN, OF PITTSBURGH, PENNSYLVANIA.

METALLIC KEG.

Application filed April 10, 1924. Serial No. 705,507.

This invention relates to metallic receptacles and the method of making the same, and particularly with respect to the class of receptacles known in the art as kegs.

5 The primary object of the invention is to so construct the keg blank that a number of the blanks may be nested together within a small space and thereby save considerable in shipping losses.

10 The invention further and more specifically comprehends the forming of the keg blank in a semi-circular manner, which upon a slight contraction may be quickly and easily joined to form a complete circular receptacle.

15 Another object of the invention is the provision of turned over upper and lower portions of the metallic material to constitute a reinforced top and bottom portion 20 of the keg adapted to withstand rough usage.

Numerous other objects of the invention will be apparent from the detailed description following when read in conjunction with 25 the attached drawings forming a part hereof, in which Figure 1 is a perspective view of the blank showing initial bending.

Figure 2 is a similar view showing a further step in the formation of the device.

30 Figure 3 is a similar view showing the device crimped and bent in a semi-circular shape ready for shipment.

Figure 4 is a view of the device ready to be sprung together to form the body of the 35 barrel.

Figure 5 is an elevation of the complete barrel.

Figure 6 is a perspective view of one of the barrel ends.

40 Figure 7 is a similar view of one of the retaining rings.

Figure 8 is an enlarged fragmentary sectional view of the device; and,

45 Figure 9 is an enlarged view of the device partly in section.

Referring now more particularly to the drawings 1 represents the body blank made of the desired material, which is preferably a galvanized or black tin metal, approxi-

mately 22 or 24 gage about 40 inches long 50 by 20½ inches wide, as clearly shown in Figure 1. The metallic blank is initially bent near the upper and lower end thereof to form reinforced upper and lower parts 2 and 3, the purpose of which will be more 55 fully explained hereinafter. The sheet is thence placed upon a suitable press and the ends thereof are punched out, as at 4, 5, 6 and 7, in order that the circular retaining ring hereinafter referred to may be utilized, 60 such punched out portions constituting a continuation of the radius of the outwardly extending grooves 7' and 8. The blank is thereafter passed between a machine possessing the necessary instrumentalities for impressing the grooves 7', 8, 9 and 10, and preferably by the same operation bending the sheet into substantially a semi-circular formation as disclosed in Figure 4 of the drawing. Cooperating laps 11 and 12, which are 65 reversely turned, are then formed in such a manner that upon the compression of the barrel body to the desired extent the ends may be securely and readily interlocked to form the completed body, as illustrated in 70 Figure 5. It will be noted that the grooves 7, 8, 9 and 10 constitute external corrugations. Additional grooves are formed, preferably by the same operation which forms the grooves aforesaid, and such additional 75 grooves are designated by the reference numerals 11' and 12'. The purpose of the grooves 11' and 12' which project inwardly with respect to the metallic body is twofold. First, in that they serve as a reinforcing 80 means for the barrel body, and secondarily, they provide cooperating shoulders for the metallic keg bottom and top 13 and 14 respectively, which bottom and top is provided with depending flanges 15 and 16 85 adapted to fit upon the shoulder formed by the grooves at the points 17 and 18.

After the metallic body structure has been sprung into a true circular form, as disclosed in Figure 5, and the cooperating lips 90 11 and 12 have been interlocked, the top and bottom are placed in the position disclosed in Figure 8. In order to securely hold the

top and bottom in place the invention contemplates the use of a retaining ring 19 of any suitable character. However, it is preferred that this retaining ring shall be of 5 the construction illustrated in Figure 7 and provided with outwardly projecting terminals 20 and 21. The metallic body is, when such a type of retaining ring is used, provided with recesses 22 and 23 into which the 10 terminals aforesaid may be placed, and the normal tendency of expansion of the retaining ring will securely and forcibly maintain the ring within the grooves 8 and 9 and thereby effectually lock the bottom and top 15 from accidental displacement. The punched out portions 4, 5, 6 and 7 permit the ring to uniformly engage within the groove of the tops and bottoms, irrespective of the longitudinal folds of the metallic receptacle 20 constituting the interlocking means therefor. The position of the ring in use is clearly illustrated in Figure 5 of the drawings.

By bending the metal intermediate its ends to form the upper and lower circumferential laps 2 and 3, I obtain an effectual reinforce for the keg at the bottom and top thereof adapted to withstand the heavy usage to which receptacles of this character are subjected.

30 It will be obvious to those skilled in the art that in order to remove the top and bottom it is only necessary to first displace the retaining rings by the insertion of any sharp instrument and to thereafter remove the 35 bottom and top thereof. The kegs are shipped in a semi-circular form and in this manner considerable storage space is saved. To set up the keg it is only necessary to spring the same together and hook the 40 reversely bent folds, which are bent longitudinally of the keg. Thence set the ends down inside of the keg preferably at a distance below the reinforced upper extremities 24 and 25 until the flanges of the tops 45 and bottoms contact with the inwardly extending grooves forming projections 17 and 18 on the interior of the keg and then applying the spring rings.

It will be obvious to those skilled in the 50 art that many changes in construction and arrangement of parts may be used without departing from the invention as expressed in the following claims.

Having thus described our invention, what 55 we claim is:

1. A metallic receptacle, comprising a body portion provided with longitudinal interlocking means, said body portion being normally of a substantially semi-circular shape, but said body portion being adapted to be sprung into substantially a circular formation and being retained in such position by the engagement of said interlocking means, a closure removably positioned within each end of the body, and means in each

end for retaining the closures in place and for preventing relative longitudinal shifting of the engaged interlocking means.

2. A metallic receptacle, comprising a body portion provided with longitudinal 70 interlocking means, said body portion being normally of a substantially semi-circular shape, but said body portion being adapted to be sprung into substantially a circular formation and being retained in such position by the engagement of said interlocking means, a closure removably positioned within each end of the body, a split ring engaging each closure to retain it in place and also to prevent relative longitudinal shifting 75 of the engaged interlocking means, and means for preventing the split in the ring from shifting into register with the interlocking means.

3. A metallic receptacle, comprising a 85 body portion provided with longitudinal interlocking means, said body portion being normally of a substantially semi-circular shape, but said body portion being adapted to be sprung into substantially a circular 90 formation and being retained in such position by the engagement of said interlocking means, said body portion being provided with turned over upper and lower end portions to form reenforced ends of double 95 thickness, and a circumferential groove forming a shoulder in abutting relation with the free edge of each turned over portion; a closure for each end provided with a flange to engage the aforesaid shoulder to limit 100 the inward movement of the closure, and means for selectively preventing outward movement of said closures and also for preventing relative longitudinal shifting of the engaged interlocking means.

4. A metallic receptacle, comprising a body portion provided with longitudinal interlocking means, said body portion being normally of a substantially semi-circular shape, but said body portion being adapted to be sprung into substantially a circular formation and being retained in such formation by the engagement of said interlocking means, said body portion being provided with an end portion bent flatly upon itself 110 to form a reenforced end of double thickness, a circumferential groove formed in the body portion to provide a shoulder with which the free edge of the bent end portion engages, a closure for said end provided with a flange 115 positioned to snugly fit the bent part of the end portion and to bear at its free edge against the shoulder of said groove, a split retaining ring to selectively prevent removal of the closure and also to prevent 120 relative longitudinal shifting of the engaged interlocking means, and means for preventing the split in the ring from shifting into register with the interlocking means.

5. A metallic receptacle, comprising a

body portion having interlocking means at opposite edges, said body portion being adapted to be sprung into substantially a cylindrical formation and being retained in such formation by the engagement of said interlocking means, a closure removably positioned in one end of the cylindrical formation, and means for retaining said closure in place and also for preventing relative longitudinal shifting of the engaged interlocking means. In testimony whereof we affix our signatures.

EDWARD DEAN MAHAN.
JAMES IRA MAHAN.
